UNITED STATES PATENT OFFICE

ALBERT L. MURRAY, OF AUBURN, INDIANA

DESIGN FOR A RUBBER SOAP DISH

Application filed March 16, 1931. Serial No. 39,107. Term of patent 3½ years.

To all whom it may concern:

Be it known that I, ALBERT L. MURRAY, a citizen of the United States, residing at Auburn, in the county of De Kalb and State of Indiana, have invented a new, original, and ornamental Design for Rubber Soap Dish, of which the following is a specification, reference being had to the accompanying drawings, forming part thereof.

I claim:

The ornamental design for a rubber soap dish, as shown.

ALBERT L. MURRAY.
